ABSTRACT

A shipping and display container formed from a one-piece sheet blank and provided with a pair of crossed fold lines dividing the container into four articulated sections. Pivotal hinged movement about either fold line provides ready access to panels of retained articles for price marking purposes.

4 Claims, 8 Drawing Figures

FIG. 6A

PIVOTALLY ARTICULATED CONTAINER WITH CROSSED FOLDS

BACKGROUND OF THE INVENTION

This application is a continuation-in-part of co-pending application Ser. No. 307,449 filed Nov. 17, 1972, now U.S. Pat. No. 3,872,965.

The present invention relates to containers for shipping merchandise to retail stores. More particularly, this invention is directed to a container having a floor formed with a pair of crossed or intersecting fold lines dividing the floor into four distinct articulated sections. Merchandise containers formed with fold lines are known in the prior art, but each of these prior art structures suffers from the disadvantage of providing only limited access to panels of articles held therein.

SUMMARY OF THE INVENTION

It is a principal object of the present invention to provide a container for shipping and storing merchandise in which price-marking indicia can be applied quickly to price panels of package units arranged in multiple layers or rows, without removing the packages from the container and without tearing or cutting the container to provide access. The container of the present invention is preformed in sections adapted to be pivotally hinged about either of two crossing fold lines, thus providing ready access either to end panels or side panels of packages on opposed sides of the respective fold lines.

It is a related object of the invention to provide a container which allows ready access to a plurality of layers or rows of packages, and which is adaptable to a great variety of sizes, arrangements and numbers of packages.

Another feature of the invention is that it is manufactured from a one-piece sheet blank without staples or glue. The preferred embodiment is inexpensive since it can be constructed from low-cost materials such as cardboard, and because no tear strips or tapes are needed.

A further object of the invention is to provide a shipping container in which retained articles can be displayed at the point of purchase.

Other objects and advantages of the invention will become apparent to those skilled in the art, from the following specification considered in conjunction with the drawings.

DESCRIPTION OF THE DRAWINGS

FIG. 1 is a perspective view of a preferred embodiment of the container of the invention, in which the container is pivotally hinged about a first fold line extending between the side walls;

FIG. 2 is a perspective view of the container of FIG. 1, with opposed hinge sections disposed to one another at an acute angle;

FIG. 3 is a perspective view of the container of FIG. 1, in which the container is pivotally hinged about a second fold line extending between the end walls;

FIG. 4 is a plan view of the container, with dotted lines indicating fold lines;

FIG. 5 is a cross-sectional view of the container of FIG. 4, taken along the line 5-5 of FIG. 4;

FIG. 6 is a cross-sectional view of the container of FIG. 4, taken along the line 6-6 of FIG. 4;

FIG. 6A is an enlargement of the encircled area of FIG. 6; and

FIG. 7 is a plan view of the planar blank used in producing the container of FIGS. 1-6, with dotted lines indicating fold lines.

DESCRIPTION OF THE PREFERRED EMBODIMENT

Referring now to FIGS. 1 through 5, there is shown a 10 container in the shape of a rectangular carton 11 having a floor 12, end walls 13 and 14, and a pair of side walls 15 and 16. A first fold line 17 extends laterally across the floor between the side walls 15, 16 and a second fold line 18 extends longitudinally across the floor 15 between the end walls 13, 14 to divide the container into four distinct sections or compartments. Each side wall is divided into two separate panels by a generally vertical slit 21 extending from an upper edge 22 to a base terminal 23 of the wall, the terminal 23 corresponding to a lateral limit of the first fold line 17. Each 20 end wall is also divided into two separate panels by a generally vertical slit 24 extending from an upper edge 25 to a base terminal 26 of the wall, the terminal 26 corresponding to a longitudinal terminus of the second fold line 18.

Flanges 27 are integrally formed with and generally coextensive with each panel of the side walls 15, 16. The flanges 27, which are joined to the side walls along fold lines 22 defining upper or outer edges of the side walls, are hinged inwardly to overlie the side walls 15, 16 and to form slots 28 coextensive with each flange 27. A downwardly projecting tab or tab means 29 projects from a free edge of each flange 27. Slits 30 are cut into lateral edges of the floor 12 at positions corresponding to the tabs 29. The flanges 27 are locked in place by intercoupling corresponding tabs 29 and slits 30.

The end walls 13, 14 are each formed integrally with a pair of flaps 35 hinged along spaced fold lines to the end walls at their lateral limits. The flaps 35 are adapted to fit within the slots 28 formed between panels of the side walls 15, 16 and their overlying flanges 27.

The container is preferably constructed from a one-piece blank, as shown in FIG. 7. The preferred embodiment illustrated is made from sheet cardboard.

The intended use of the container is best understood upon reference to FIGS. 1 and 3. The carton 11 is provided with a cover (not illustrated) in order to protect and secure merchandise packages therewithin during shipment and storage. When the outer wrapping is removed it is generally desired to apply price-markings to panels of the packages. When the carton 11 is pivoted about its first or laterally extending fold line 17 as shown in FIG. 1, one set of package panels is exposed to view. An additional set of package panels is exposed when the carton 11 is pivotally hinged about its second or longitudinally extending fold line 18, as shown in FIG. 3. By providing arcuate hinging in two different directions, the container affords access to price-marking panels of merchandise packages regardless of whether these package panels are exposed in the mode shown in FIG. 1 or that shown in FIG. 3. Accordingly, price marking indicia can be applied to all package units without removing them from the container, regardless of whether the panels to be marked face the first fold line 17 or the second fold line 18. Additional fold lines (not shown) parallel to the first and second

fold lines 17, 18 are provided when needed to provide even greater access to package panels.

The foregoing description of the invention is with reference to one preferred embodiment. The invention is not to be limited to all of the details shown in this description, but is capable of modification and variation within the spirit and scope of the following claims.

What is claimed is:

1. In a shipping and display container adapted to hold a multiplicity of packages in an organized array, said container comprising a pair of opposed side walls, a pair of opposed end walls, and a uniplanar floor joined to said side walls and said end walls, the improvement wherein:

a. said floor is formed with a first fold line extending laterally thereacross between said side walls and a second fold line extending longitudinally thereacross between said end walls to provide four floor joined, pivotally articulated sections connected along the fold lines in said floor;

b. said side walls are formed with opposed, generally vertically directed slits extending from upper edges of respective said side walls downwardly to said floor at said first fold line to divide each of said side walls into two distinct panels, whereby said floor is adapted for unrestricted hinged arcuate movement downwardly about said first fold line; and

c. said end walls are formed with opposed, generally vertically directed slits extending from upper edges of respective said end walls downwardly to said floor at said second fold line to divide each of said end walls into two distinct panels, whereby said floor is also adapted for unrestricted hinged arcuate movement downwardly about said second fold line;

each said sections being adapted to hold a row of articles extending thereacross, whereby upon pivotal shifting of said sections about either of said first

and second fold lines in said floor to open said slits in said walls, panels of any articles contained in respective said sections are exposed and rendered readily accessible for application of price marking indicia thereto.

2. The structure as set forth in claim 1, wherein said container is formed from a uniplanar, one-piece blank.

3. The container as set forth in claim 1, wherein

a. each said side walls includes a pair of flanges hinged thereto along a fold line defining an upwardly facing upper edge thereof, each said flanges extending downwardly of said upper edge and overlying each said side walls in proximity thereto, whereby each said flanges and respective said side walls, define therebetween a slot coextensive with said flanges;

b. said container further comprises means securing said flanges in place; and

c. each said end walls includes a pair of flaps hinged thereto along spaced fold lines defining lateral limits thereof;

each one of said pair of flaps extending generally normal to said end walls to parallel said side walls and to project into a corresponding said slot, thereby to interlock said floor, said end walls, and said side walls into a stable, unitary structure.

4. The container as set forth in claim 3, wherein said means securing each one of said pair of flanges in place comprise slits formed in said floor adjacent lateral limits thereof and paralleling lateral edges of said floor, and further comprising downwardly projecting tab means integrally formed with each one of said pair of flanges at downwardly directed free ends thereof, each said tab means projecting into and seating within a corresponding said slit in said floor to lock the flanges in place.
